UNITED STATES PATENT OFFICE

CARLOS ANTONIO GORSSE, OF BUENOS AIRES, ARGENTINA

LUMINOUS SCREEN FOR ADVERTISING PURPOSES

Application filed September 28, 1928, Serial No. 308,906, and in Argentina February 7, 1928.

This invention relates to luminous advertising devices and proposes a device of this type which may be used at the same time for advertising purposes and for the display 5 both by day and night of traffic signs, street markings and other indicia.

An object of the invention is to provide for the display of legends or other indicia which may be easily read in more than one 10 direction; and further the invention contemplates a number of separate sign-carrying units having one common source of illumination which may be employed for a variety of display indications.

Another object of the invention is to provide means which will facilitate the installation and removal of the display screens; and at the same time permit ready access 20 to the illuminating chamber for the purpose of making repairs and replacements.

The invention has been illustrated in the accompanying drawings showing one preferred embodiment thereof, and in which:

Fig. 1 is a front elevation of the whole device;

Fig. 2 is a section through the upper part, or screen frame, with parts removed to clearly show the interior thereof;

Fig. 3 is a front elevation of the ring member supporting the transparent screen;

Fig. 4 is a similar view of the ring member designed to secure the screen in position on its supporting ring; and

Fig. 5 is a cross-sectional view of the upper portion of the device, showing one complete side thereof.

In these drawings, similar parts have been designated by like characters of reference throughout the several views.

The unit according to the invention comprises a standard or foot 1 of any approved shape and size, on the upper portion of which is secured a frame 2 preferably of oval form. This frame is of hollow formation in its vertical cross-section, so as to allow for the necessary space for accommodation of the internal illuminating devices, preferably electric lamps, and forms with each of its two sides a ring support for securing thereto 50 one of the two screens bearing the legends

or images for advertising purposes. The upper portion of the said frame 2 is provided with cut-away portions 3-4 facing in both directions and adapted to contain therein plates of glass or other transparent material, which may bear inscriptions or legends relating to traffic or other conditions. At the upper portion of the standard 1, at positions corresponding with the front and rear of the frame 2, there is provided a further cut-away portion 5 of circular form which also may be provided with a transparent plate bearing inscriptions. At any convenient position of the standard 1 there may be provided a cover or lid giving access to electrical connections or the like.

The frame 2 is provided at each of its sides with a ring member 6 secured thereto by means of screws or the like, and the holes 7, and at its inner periphery the ring member 6 is formed with a recess 8 for accommodation of the glass, or other, screen 9 bearing the advertising matter. The screen 9 is secured in position by means of a further ring member or keeper 10 which is inserted behind the projections 11, 11^a of the standard 1, and fixed to the ring member 6 by means of a screw or the like and the hole 12. At the inner side of the frame 2 there are disposed the lamp-sockets 13 and electric lamps 14, which provide for, or constitute, the internal light source for illuminating the device at night time.

In practice, after removing the ring member or keeper 10, the screen or transparent plate 9 may be easily withdrawn and substituted by another one bearing different legends or inscriptions which, then, is secured in place superimposed on the ring member 6 and securing again the ring member 10 to the latter in the manner described. The screen 9, as well as the plates secured over the cut-away portions 3, 4 and 5, are of a transparent nature so that the internal light source will clearly display to the public any description or legend thereon provided.

Having thus fully described my said invention, what I claim and desire to secure by Letters Patent is:—

1. An advertising device comprising an annular illuminating chamber formed to pro-

vide viewing apertures in each face of said chamber, a supporting standard for the chamber carrying spaced lugs adjacent the point of attachment to said chamber, a plurality of lamps lying wholly within the chamber, a ring member provided with a circumferential inner groove and adapted to fit each aperture of said chamber, means for attaching said ring and chamber, a display screen to fit the groove of each ring, a detachable keeper for each screen having one portion of its edge inserted beneath the aforesaid lugs and means coacting with said lugs for clamping each screen in position relatively to its respective ring.

15 2. An advertising device comprising an annular illuminating chamber, formed with cut-away portions in each face to provide viewing apertures in said chamber, a supporting standard for the chamber having spaced lugs adjacent the point of attachment to said chamber, a plurality of lamps lying wholly within the permanently enclosed portion of the chamber, a ring formed with a circumferential inner groove, said ring being secured to the said chamber and having its inner edge substantially co-extensive with each aperture, means for attaching said ring on each face of said chamber, a translucent display screen adapted to fit the groove of said ring, a detachable keeper adapted to overlie each screen, said keeper being secured at one edge in the aforesaid lugs and means at its opposite edge co-active with said lugs for clamping each screen between its respective ring and keeper.

In testimony whereof I affix my signature.
CARLOS ANTONIO GORSSE.
